UNITED STATES PATENT OFFICE.

GEORGE SUMMERS CROTTs, OF PHILADELPHIA, PENNSYLVANIA.

GLASS-BATCH MIXER.

SPECIFICATION forming part of Letters Patent No. 284,121, dated August 28, 1883.

Application filed June 2, 1883. (Model.)

To all whom it may concern:

Be it known that I, GEORGE SUMMERS CROTTs, of Philadelphia, in the county of Philadelphia and State of Pennsylvania, have invented a new and useful Improvement in 5 Glass-Batch Mixers, of which the following is a full, clear, and exact description.

Reference is to be had to the accompanying drawings, forming a part of this specification, 10 in which similar letters of reference indicate corresponding parts of both the figures.

Figure 1, Sheet 1, is a sectional plan view 15 of my improvement, parts being broken away; and Fig. 2, Sheet 2, is a sectional side elevation of the same with parts broken away.

The object of this invention is to economize time, labor, and expense in preparing batches 20 for glass-furnaces, and also to promote thoroughness in the preparation of such batches.

The invention consists in a batch-mixer constructed with a series of elevators and a box 25 and a discharge-slide and their spouts for introducing the material into the mixing-cylinder, where it is thoroughly mixed and then discharged upon the screen, so that the material will be mixed and screened with one handling, as will be hereinafter fully described.

A represents bins to receive the sand, soda- 30 ash, and lime, which bins are represented in the drawings as standing upon the floor, but which in practice are designed to be placed in openings in the floor with their tops flush with the surface of the said floor, so that the materials can be shoveled from the floor into the

35 said bins without being lifted. The materials are taken from the bins A by the buckets B of elevators, the endless belts C of which pass around pulleys D, pivoted within the said bins, and around pulleys E, attached to the

40 drive-shaft F, placed in the upper part of the building. The buckets B are graduated in size, so that the proper relative quantities of the materials will be taken from the bins, and the necessity of weighing the said materials

45 will be avoided. The materials are discharged from the buckets B into the spouts G, by which they are conducted into the hopper H of the mixing-cylinder I. Into the hopper H is also introduced, through the spout J, salt from the 50 box or bin K. The salt is removed from the box K and discharged into the spout by a slide, L, which has an aperture, M, formed through

it of such a size as to contain the amount of salt to be added to the other ingredients at a time. The slide L discharges the salt through 55 an opening, N, in the bottom of the box K, beneath the cut-off O, so that no more salt can be discharged at each movement of the slide L than the full of the aperture M.

To the end of the slide L that projects 60 through an opening in the end of the box K is attached the end of a pitman, P, the other end of which is pivoted to the crank Q, the journals of which revolve in bearings attached to the frame of the building, and to one of the 65 said journals is attached a pulley, R. Around the pulley R passes a belt, S, which also passes around a pulley, T, attached to the drive-shaft F. To the other end of the shaft F is attached a fast pulley, U, and a loose pulley, V, to receive the driving-belt. To the 70 shaft F is also attached a pulley, W, around which passes a belt, X. The belt X also passes around a pulley, Y, attached to the shaft Z, which passes through the cylinder I and revolves in bearings attached to the frame of the 75 building or other suitable support.

To the shaft Z, within the cylinder I, are attached a number of radial arms or paddles, 1, by the action of which the materials are thoroughly mixed as they pass through the said cylinder I. The material is discharged from the cylinder I into the screen 2, through which the fine material falls into the batch-carts, by which it is carried to the furnace. Any lumps 80 that may be in the materials fall from the lower end of the screen 2 into some suitable receiver. The upper end of the screen 2 is pivoted to a post, 3, or other suitable support, and its lower end is supported from the frame 85 of the building by rods 4, as shown in Figs. 1 and 2.

To the side of the lower end of the screen 2 is hinged the end of the connecting-rod 5, the other end of which is attached to the end of 90 the arm 6, attached to the shaft 7. The shaft 7 is vertical, and revolves in bearings connected with the frame of the building, and to it is attached a second arm, 8, to the outer end of which is attached the end of a connecting-rod, 9. The other end of the rod 9 is pivoted to a crank-pin or crank, 10, attached to a small gear-wheel, 11, pivoted to the support for the journal of the cylinder-shaft Z, or to other

suitable support. The teeth of the gear-wheel 11 mesh into the teeth of the larger gear-wheel 12, attached to the cylinder-shaft Z, so that the screen 2 will be vibrated from the said shaft.

5 With this construction the materials will be delivered into the cylinder I in proper relative quantities, will be thoroughly mixed while passing through the said cylinder, and will be screened and delivered to the batch-carts with 10 one handling, so that the time and labor required in preparing the batch, and consequently the cost, will be greatly lessened, while the work will be more thoroughly done than is possible with hand-mixing.

15 Having thus fully described my invention, I claim as new and desire to secure by Letters Patent—

1. The combination, with a mixer, of a single hopper, H, inclined spouts leading thereinto, 20 and suitable means for supplying said spouts with a definite proportion of each ingredient at their upper ends, whereby the several ingredients are brought together in their required proportions as they enter the mixer.

25 2. In a batch-mixer, the combination, with the mixing-cylinder I, of the series of spouts G and graded elevators B C, substantially as herein shown and described, whereby several 30 materials can be introduced in proper proportions into the same cylinder and mixed, as set forth.

3. In a mixer, the combination, with vessels holding the several ingredients to be mixed, of elevators arranged on the same shafts, having their respective buckets graduated in size 35 to suit the proportions required of the different ingredients and passing into the said vessels, whereby the buckets of all the elevators move synchronously and continuously carry up definite proportions of the ingredients, as 40 described.

4. In a batch-mixer, the combination, with the mixing-cylinder I, of the spout J, the box K, and the discharging-slide L, substantially as herein shown and described, whereby the 45 substance in the said box will be introduced into the mixing-cylinder at regular intervals and in uniform quantities, as set forth.

5. In a batch-mixer, the combination, with the mixing-cylinder I, of the graded elevators 50 B C, the box and discharge-slide K L, the spouts G J, the screen 2, and a driving mechanism, substantially as herein shown and described, whereby the various ingredients for a batch are mixed and screened at one opera- 55 tion, as set forth.

GEORGE SUMMERS CROFTS.
